RAIL CROSSING

John A. Johnson, Denison, Tex., assignor, by
mesne assignments, to The American Brake
Shoe and Foundry Company, New York, N. Y.,
a corporation of Delaware

Application February 2, 1937, Serial No. 123,565

8 Claims. (Cl. 246—379)

This invention relates to rail crossings and more particularly to an improved movable center point crossing.

In the construction of movable center point crossings it has been customary to provide movable point rails which are hinged to fixed rails and which are supported, when in closed position, only by the hinged connection and by abutment of the rail point against the cooperating knuckle rail. Such movable point rails are inherently weak because they are relatively unsupported against thrust and overturning. Because of this inherent weakness, the movable point rails are made relatively short and the fixed rails are extended to points close to the knuckle rails. The points, being relatively short, have to be moved through relatively large angles between open and closed position and hence sufficiently flexible joints must be provided between the fixed rails and the movable point rails to permit movement through these relatively large angles. Furthermore, it has been found difficult to maintain proper alignment of the various portions of movable center point crossings owing particularly to track creepage.

According to the present invention, there is provided a movable center point crossing wherein the movable point rails, when in closed position, are reinforced by suitably positioned, fixed, reinforcing or brace rails which support and prevent overturning of the movable point rails. Each point rail is supported throughout substantially its entire length and therefore can be of considerable length, the hinge connection being located adjacent the end frogs of the crossing. Since the ends of the movable point rails have a relatively long radius of movement, less flexibility is required at the joint than previously, and the joint can be made relatively strong and rugged.

The brace rail preferably is connected at its ends to the corresponding inside or wing rail and to the opposite knuckle rail respectively in such a manner as to provide a strong rigid connection between these rails. Where four such brace rails are connected to the rails constituting a crossing, a rigid truss-like crossing is provided in which creeping of the stock rails and consequent misalignment and disarrangement of the connections is minimized.

Various other features and advantages of the invention will be apparent from the following particular description and from an inspection of the accompanying drawings.

Although the novel features which are believed

to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a diagrammatic top plan view of a crossing constructed in accordance with the invention;

Fig. 2 is a top plan view showing the structure of the principal portions of one-half of the crossing illustrated diagrammatically in Fig. 1;

Fig. 3 is an enlarged cross-sectional view taken along line 3—3 of Fig. 2;

Fig. 4 is an enlarged fragmentary view of the portion of the structure shown in Fig. 2, at the joints between the movable points and the inside rails, certain of the structure being shown in cross section for the purpose of clear illustration;

Fig. 5 is an enlarged cross-sectional view taken along line 5—5 of Fig. 4; and

Fig. 6 is an enlarged fragmentary view of a portion of the structure at the knuckle and the adjacent end of the brace rail, portions of the structure being shown in cross section for the purpose of clear illustration.

In the following description and in the claims, various details will be identified by specific names for convenience, but they are intended to be as generic in their application as the art will permit. Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

One form of crossing in which the present invention is embodied is shown diagrammatically in Fig. 1. Inasmuch as the construction of the crossing on both sides of the transverse center line are similar, only the left-hand half of the crossing is shown in the structural views and described in the following description; it will be understood that the following description applies equally as well to the right-hand half of the crossing. The structure in the present embodiment is not truly symmetrical since for the purpose of illustration, there has been selected a crossing between a straight track and a curved track of long radius.

Referring also to Fig. 2, the crossing includes outside stock rails 1 and 2, and a frog 3 including inside or point rails 4 and 5 and inside or wing rails 6 and 7, all of which are mounted on suitable ties 8. Knuckle rails 9, 10 are connected to the ends of the stock rails 1 and 2 and are mounted on slide plates 11 suitably secured on certain of the ties 8. A set of third or easer rails 11, 12 are disposed on the outside of each knuckle rail and each has one or more rail braces 13 associated therewith and secured on the corresponding slide plates 11. It will be understood that a suitable number of slide plates of suitable lengths are provided for supporting the several portions of the crossing hereinafter described, which slide plates need not be described in detail inasmuch as the construction and operation will be apparent from the drawings.

Movable point rails 15 and 16 extend from the inside or wing rails 6 and 7 to the knuckle rails 9 and 10 respectively. The movable point rails 15 and 16 are connected by a suitable number of switch rods 17 attached to jaw clips 18 which are in turn connected by bolts 19 to the point rails 15 and 16 thereby spacing and rigidly connecting the point rails. If desired, a reinforcing bar 19' may be clamped against the web of each movable point rail by the bolt 19.

A reinforcing easer rail 20 may be secured to the outside of each movable point rail adjacent the point to provide a bracing and reinforcing member. The member 20 preferably is suitably tapered to fit between the end of the movable point rail and the knuckle rail when the former is in closed position.

The movable point rail 15 is connected to the inside or wing rail 6 by a flexible joint designated generally by the reference character 22, the construction of which joint will be described more in detail hereinafter. Extending between the end of the inside or wing rail 6 and the opposite knuckle rail 9 is a brace rail 25 which is connected to the inside or wing rail 6 at or adjacent the joint 22 and to the knuckle rail 9 at a connection designated generally by the reference character 26.

It will be understood that in most cases the movable point rail will be connected directly to the wing rail. However, in certain cases, it may be found desirable to interpose a fixed rail between the wing rail and the heel end of the movable point rail. In such a case, preferably the brace rail is connected to this interposed fixed rail and the knuckle rail. Where the "inside rail" is referred to, it will be understood to designate either the wing rail or the aforesaid fixed rail extending from the wing rail.

Referring also to Fig. 4, the joint 22 includes an angle bar 27 having a head 28 adapted to fit under the head or ball of the movable point rail 15, a web 29 and a flange 30 adapted to fit against the flange of the movable point rail 15. The angle bar 27 cooperates in a similar manner with the end portion of the inside rail 6.

The angle bar 27 is connected to the movable point rail 15 and inside rail 6 by a plurality of bolts 31, at least one of which extends through the angle bar 27, the inside rail 6 and the brace rail 25 and another of which extends through the angle bar 27, movable point rail 15 and brace rail 25. The bolts 31 are secured as by nuts 32 and spring washers 33; if desired, a reinforcing plate 34 may be interposed between the spring washer 33 and the web of the brace rail 25.

A filler block 35 having a groove 36 may be

interposed between the brace rail 25 and the abutting ends of the inside rail 7 and the movable point rail 15 and may be clamped between these rails by the bolts 31.

Flexibility of the joint may be provided by bending or curving the angle bar 27 longitudinally so that the end adjacent the movable point rail 15 stands away from the filler block 35. The openings 37 and 38 in the flange of the movable point rail 15 may be sufficiently larger than the corresponding bolts passing therethrough to permit freedom of movement of the movable point rail 15. If desired, a thimble 39 may extend through the opening 37 and may surround the corresponding bolt 31 to positively space the end of the angle bar 27 away from the filler block 35 and permit relatively free movement of the movable point rail 15.

Referring now to Fig. 3, the brace rail 25 may be supported against movement on the slide plates 11 by braces 40 each having a side portion 41 engaging the side of the brace rail 25 a base or foot 42 resting upon the slide plate 11 and a reinforcing or stiffening web 43. The brace 40 may be secured to the slide plates as 25 by rivets 44, and may be still further held against displacement by a stop 45 secured to the slide plate 11 as by one or more rivets 46. The stop plate may also be welded to the slide plate as indicated at 47. The brace rail may 30 be prevented from moving away from the brace 43 by a rib or other abutment, such as the welded rib 48.

Movement of the movable point rail 15 toward the brace rail 25 may be halted by one or more 35 stops 50, each of which includes arched or V-shaped projecting portion 51, and flange portions 52 secured to the web of the movable point as by bolts 19. Preferably, the stops are made in the form of bent straps of generally V or U-shaped cross sections.

Referring now to Fig. 6, the joint or connection 26 between the knuckle rail 9 and the adjacent end of the brace rail 25 may be broadly similar to the connection 22. The connection 45 26 preferably includes an angle bar 60 abutting the knuckle rail 9, a tapered filler block 61 interposed between the knuckle rail 9 and the end of the brace rail 25 and one or more bolts 62 passing through the angle bar 60, knuckle rail 9, filler block 61 and brace rail 25. Each bolt may be secured by a nut 62', spring washer 63 and taper washer 64 to provide a strong and rigid connection between the knuckle rail 9 and the end of the brace rail 25.

It will now be seen that each movable point rail 15 is of substantial length and extends from the knuckle rail to a joint which may be closely adjacent the end frog. Thus the movable point rail has a relatively long radius of movement and the flexible joint need provide for only a relatively small amount of angular movement of the movable point rail. The heel joint connecting the movable point rail to the inside rail can be relatively strong since relatively little flexibility is required. The easer rail fixed to the point end of the movable point rail provides ample support and reinforcement for this portion of the rail.

The strong, firmly secured brace rail extending between and rigidly secured to the fixed rails provides a highly effective reinforcing and bracing arrangement for the movable point rail when the latter is in closed position. The brace rail is spaced from the movable point rail when the latter is in closed position and does not interfere 75

in any way with the function of the latter but serves both to brace and prevent overturning of the movable point rail. The movable point rails are connected throughout their lengths and even though of considerable length, form with their connections a strong relatively rigid unitary movable structure.

The brace rails are firmly connected to the fixed rails and provide in effect a unitary double truss frame which is solidly connected and which resists any tendency of the rails to creep. This strong unitary frame is rigidly connected to the track structure and thus insures that the knuckle rails and movable center points will be maintained in proper arrangement and alignment and will operate satisfactorily under all conditions.

While certain novel features of the invention have been disclosed and are pointed out in the annexed claims, it will be understood that various omissions, substitutions and changes may be made by those skilled in the art without departing from the spirit of the invention.

What is claimed is:

1. A movable center point crossing including intersecting pairs of parallel rails, knuckle rails connecting the outside rails of said pairs, end frogs associated with the inside rails, said end frogs including wing rails, movable point rails extending between said wing rails and said knuckle rails, brace rails extending between said knuckle rails and said wing rails, and means for connecting said movable point rails to said wing rails, said last means including fastening members extending through said brace rails and said wing rails and fastening members extending through said brace rails said movable point rails, and means connecting said brace rails and said knuckle rails including fastening members extending through said brace rails and knuckle rails.

2. In a movable center point rail crossing, sets of outer and inner rails on opposite sides of the center, a set of knuckle rails, each knuckle rail connecting its corresponding outer rails, a set of frogs, each frog comprising a frog point and wing rails, each set of said inner rails being connected to its respective frog point, sets of point rails, one set of point rails being on each side of the center and each point rail of each set being hingedly connected to its particular wing rail, sets of brace rails, each brace rail being disposed on the outside of its point rail, connecting assemblies, each connecting assembly positively fastening its respective brace rail to the adjoining knuckle rail, hinge assemblies, each hinge assembly positively fastening its respective brace rail to its respective point rail, said brace rails and knuckle rails tying together said frogs and preventing relative track creepage therebetween.

3. In a movable center point rail crossing, sets of outer and inner rails on opposite sides of the center, a set of knuckle rails, each knuckle rail connecting its corresponding outer rails, a set of frogs, each set of said inner rails being connected to its respective frog, sets of point rails, one set of point rails being on each side of the center and each point rail of each set being hingedly connected to its particular inner rail, sets of brace rails, each brace rail being disposed on the outside of its point rail, connecting assemblies, each assembly positively fastening its respective brace rail to the adjoining knuckle rail, hinge assemblies, each hinge assembly positively fastening its respective brace rail to its respective inner rail and hinging its respective point rail, said brace

rails and knuckle rails tying together said frogs and preventing relative track creepage therebetween.

4. In a movable center point rail crossing, sets of outer and inner rails, frogs connecting the inner rails, means connecting the outer rails on opposite sides of the crossing center, brace rails positively fastened to said outer rails; point rails, hinge assemblies for said point rails, each said hinge assembly connecting its respective point rail, brace rail and inner rail, each said hinge assembly comprising a spacer block located between the brace rail on the one hand and the aligned point rail and inner rail on the other, a bar located on the inner side of said point rail and inner rail, said bar having a deflected end bent away from said spacer block, fastening members passing through said bar, inner rail, spacer block and brace rail to fasten these members together, additional fastening devices passing through the deflected end of said bar, point rail, spacer block and said brace rail, and means to give hinge action to said point rail.

5. In a movable center point rail crossing, sets of outer and inner rails, frogs connecting the inner rails, knuckle rails connecting the outer rails on opposite sides of the crossing center, brace rails positively fastened to said knuckle rails; point rails, hinge assemblies for said point rails, each said hinge assembly connecting its respective point rail, brace rail and inner rail, each said hinge assembly comprising a spacer block located between the brace rail on the one hand and the aligned point rail and inner rail on the other, an angle bar located on the inner side of said point rail and inner rail, said angle bar having a deflected end bent away from said spacer block, fastening members passing through said angle bar, inner rail, spacer block and brace rail to fasten these members together, additional fastening devices passing through the deflected end of said angle bar, said point rail, spacer block and brace rail, certain of said additional fastening devices having a spacer between said angle bar and spacer block, said point rail having a clearance hole for said spacer to give hinge action to said point rail.

6. A movable center point rail crossing including sets of inner and outer rails on opposite sides of the center, knuckle rails connecting the outer rails, end frogs having wing rails associated with the inner rails, movable point rails, means hingedly connecting said movable point rails to said wing rails, brace rails extending between said knuckle rails and said wing rails in position to brace said movable point rails respectively when the latter are in closed position, means tightly fastening one end of said brace rails to said knuckle rails, and means tightly fastening the other end of said brace rails to said wing rails to prevent relative creepage of the end frogs of the crossing.

7. A movable center point rail crossing including sets of inner and outer rails on opposite sides of the center, knuckle rails connecting the outer rails, end frogs associated with the inner rails, movable point rails extending from the ends of said inner rails to said knuckle rails respectively, means hingedly connecting said movable point rails to the ends of said inner rails, brace rails extending from said inner rails to said knuckle rails, means tightly fastening one end of said brace rails to said inner rails, and means tightly fastening the other end of said brace rails to said knuckle rails, whereby said frogs and knuckle

rails are united into a unitary and continuous rail assembly.

8. A movable center point rail crossing including sets of inner and outer rails on opposite sides of the center, movable point rails extending between the inner and outer rails of said sets, means hingedly connecting said movable point rails to said inner rails for movement between open and closed positions, brace rails extending between the inner and outer rails of each set, means tight-

ly fastening one end of said brace rails to said inner rails, means tightly fastening the other end of said brace rails to said outer rails, to prevent relative track creepage, and stop means distributed substantially throughout the length of said brace rails and movable point rails, whereby said brace rails provide lateral support to said movable point rails when said movable point rails are in closed position.

JOHN A. JOHNSON. 10
